UNITED STATES PATENT OFFICE.

CARL H. KADIE, OF STRASBURG, VIRGINIA, ASSIGNOR TO STARK CAR COUPLER CORPORATION, OF STRASBURG, VIRGINIA, A CORPORATION OF VIRGINIA.

CAR-COUPLING.

1,107,959.

Specification of Letters Patent.

Patented Aug. 18, 1914.

Application filed August 18, 1913. Serial No. 785,235.

To all whom it may concern:

Be it known that I, CARL H. KADIE, a citizen of the United States, and a resident of Strasburg, in the county of Shenandoah 5 and State of Virginia, have made certain new and useful Improvements in Car-Couplings, of which the following is a specification.

My invention relates to car couplings of 10 the general type known as Master Car Builders' automatic couplings, the general purpose of which is to reduce to a minimum the dangers peculiar to the coupling of cars and also to save time in coupling. This is 15 accomplished by rendering the coupling more efficient, reliable, safer and more convenient to operate and to obviate the necessity of train men going between the cars for the purpose of coupling and uncoupling 20 same.

My invention comprehends a number of 25 improvements in car couplers of this kind, and among the objects sought to be obtained by these improvements are the following: I. To render the throw or outward swing of the knuckle complete and positive; that is to insure that the knuckle, when the lock pin is raised or moved upward will always swing to a predetermined outer limit. II. To prevent 30 the complete removal of the lock pin from its mountings and in so doing to prevent excessive travel of the knuckle when thrown open by movement of the pin. III. To support the lock pin in an elevated position, when once raised thereto, until the 35 knuckle is completely closed and locked by the dropping of the pin. IV. To prevent the lock pin, when in its lowermost position, from creeping upward in consequence of 40 draw strains upon the knuckle or of slight movement of the knuckle and parts associated therewith while the coupling is in action. V. To insure the complete closure of the knuckle independently of the pressure 45 upon its outer face when a mating knuckle or analogous coupling member is thrust into the coupling head for the purpose of connecting two pieces of rolling stock together. These objects and others are attained by my 50 invention, as hereinafter more particularly pointed out.

Reference is made to the drawing forming a part of this specification, and in which like characters indicate like parts.

Figure 1 is a plan view of my improved

coupling, one of the movable knuckles of which is here shown as being closed independently of the pressure upon its outer face. Fig. 2 is a substantially central horizontal section through one of the draw heads, 60 showing the movable knuckle as open or swung outwardly to its limit of travel. Fig. 3 is a section somewhat similar to Fig. 2 but showing the knuckle as closed or swung inwardly to its limit of travel. Fig. 3^a is a 65 fragmentary side elevation of one of the draw bars, certain parts being broken away so as to show how the lock pin is supported in an elevated position except when the knuckle is completely closed. Fig. 4 is a 70 vertical section on the line 4-4 of Fig. 3 looking in the direction of the arrows. Fig. 5 is a detail view showing the movable knuckle, together with the locking pin for controlling said knuckle. Fig. 6 is a detail 75 view showing in perspective the locking pin. Fig. 7 is a detail showing in perspective the lower portion of the locking pin and also showing fragmentarily the cam controllable by movement of the locking pin, for actuating the movable knuckle. 80

Two draw bars are shown at 8 and are in this instance exactly alike. One side of the longitudinal center of each draw bar is provided with an elongated pocket or way 9 85 closed at its rear end and movably fitted into this pocket or way is a movable guard arm 10 which may be of the usual or any desired construction. This movable guard arm is provided with a stem 11 which extends through a cylindrical bearing 12 and encircling the stem is a spiral spring 13 abutting at one end against the cylindrical bearing 12 and at its opposite end against the adjacent portion of the movable guard 90 arm 10. The movable guard arm 10 is provided with a shoulder 14 adapted to fit neatly against the locking pin as hereinafter described. 95

A movable knuckle 15 is journaled upon a 100 knuckle pin 16, this pin extending through a hole 17, with which the knuckle is provided as may be understood from Fig. 5. The knuckle 15 is provided with a tail 18, this tail having a portion 20 of arcuate form 105 and being integral with the knuckle. The tail 18 is further provided with a lug 19 integral with it, the upper face of this lug being inclined as indicated in Fig. 4. The portion 20 of the tail 18 is provided with a 110

downwardly extending flange 22, constituting a shoulder or hook, for the purpose hereinafter described. The portion 20 of the tail 18 is further provided with an inclined face 21.

The locking pin is shown at 23 and is provided at its top with an eye 24 by aid whereof the pin is raised or lowered in the usual or any desired manner. The pin 23 is further provided with a notch 25 which is bounded at its top by a shoulder 26, and at its bottom by a shoulder 27. The shoulder 26 is horizontal and the shoulder 27 is inclined as indicated in Fig. 4. The locking pin 23 is provided adjacent its bottom end with a lug 28 integral with it, the upper face of this lug being slightly rounded at the point where it connects with the adjacent portion of the pin.

The draw head is provided with strengthening ribs 29 and with an extending portion 30, the latter being provided in order to accommodate the adjacent portion 20 of the tail 18 when this tail is swung to its limit in a contra-clockwise direction, according to Figs. 2 and 3. The guard arm 10 is provided with an arcuate surface 31, the curvature of which conforms to the outer curvature of the portion 20 of the arm 18. The draw head is provided with beads 32 (see Fig. 4) which are practically enlargements of the bearing surfaces engaged by the coupling pin 23. When the movable guard arm 10 is in its normal position as indicated in Figs. 2 and 3, the shoulder 14 is pressed against the locking pin 23.

When the knuckle 15 is subjected to pulling strain—that is when the coupling is in actual use for pulling rolling stock—the tail 18 presses hard against the locking pin, forcing it to the right according to Fig. 4. This leaves a small space 34 at the left of the locking pin according to this figure and causes the lug 28 to extend slightly under the adjacent bottom portion of the draw head. The lug 28, being unable to move upwardly, holds the locking pin down and prevents it from creeping upward as it would tend to do otherwise. The locking pin 23, being forced to the right, also engages the shoulder of the movable guard arm 10 and prevents it from moving inwardly. Suppose, however, that the knuckle is thrown outwardly to the limit of its travel, as indicated in Fig. 2. The shoulder 22 now rests against the pin 23, and though the knuckle 15 is not now subjected to any strain, the shoulder 22 nevertheless exerts a slight pressure against the locking pin, tending to force it to the right according to Fig. 4. This may be understood from Fig. 2, assuming that the knuckle 15 and arm 18 are turned in a clockwise direction to their limits of travel, so that the shoulder 22 lodges 65 against the locking pin.

The operation of my device is as follows: I will first assume that the knuckle is closed and the locking pin 23 is in its lowermost position as indicated in Figs. 3 and 4. If now the locking pin 23 be lifted upward to the limit of its travel, the shoulder 27, while engaging the cam surface 21 and pressing upwardly thereagainst causes the tail 18 to turn in a clockwise direction, according to Fig. 2, so that the knuckle 15 is opened or thrown outward to the limit of its travel, as indicated in this figure. That is to say, the tail 18 is turned angularly upon the knuckle pin 16 as a center, so that the flange 22 or shoulder lodges against the locking pin 23. Since after reaching this position, the tail 18 can turn no farther, the portion 20 of the tail 18 is unable to free itself from the locking pin, and therefore the locking pin cannot be lifted out of the draw head, no matter how suddenly the locking pin may be raised upward. Nor can the tail 18 be turned sufficiently to permit the locking pin to drop behind it, as would be the case otherwise. The locking pin cannot be disconnected from its mountings and when the flange 22 lodges against the pin, not only is the pin locked to prevent it from moving upwardly, but it is also for the moment prevented from moving downwardly and the knuckle 15 is prevented from moving any farther outwardly. Moreover, as the pin 23 is raised upward, the knuckle 15 is thrown open and moved positively to the outward limit of its travel. With the parts in this position the pin 23 is held up by resting upon the portion 20 of the tail 18, and thus is virtually locked so long as the knuckle retains the position it now occupies. The pin, though prevented from dropping with the knuckle in the position just mentioned, is nevertheless free to drop by its own weight whenever the knuckle 15 is swung inwardly to the limit of its travel as indicated in Fig. 3. Suppose now that two draw heads are brought together, as indicated in Fig. 1. Ordinarily, the knuckles 15, by pressure upon their outer faces due to the adjacent guard arm 10, are swung inwardly and closed. If, for any reason, however, either of the knuckles fails to close from pressure exerted upon its outer face, the knuckle 15 of the opposite draw head, by pressing against the lug 19, swings the tail 18, and in so doing, turns or closes the knuckle 15. In operating my improved draw head in connection with an ordinary old-style coupling member, if the member last mentioned fails to exert pressure on the outer face of the knuckle 15 so as to close the same, the coupling member will indirectly close the knuckle 15 by exerting pressure upon the lug 19, as indicated in Fig. 1. No matter whether the knuckle 15 be subjected to pulling strain or not, the locking pin 23 is forced to the right, according 120 125 130

to Fig. 4, so that the lug 28 prevents the locking pin from creeping upward, as above explained.

I do not limit myself to the precise arrangement shown, as alterations may be made without departing from the spirit of my invention.

Having thus described my invention, what I claim as new and desire to secure by Letters Patent is as follows—

In a car coupling, the combination of a draw head, a knuckle journaled to swing with respect to said draw head and having a tail provided with a cam portion extending inwardly and with a lug projecting outwardly, the upper surface of which lug is below the upper surface of the tail and inclined downwardly away from the tail, a locking pin mounted through the draw head to move vertically and having a shoulder engageable beneath the cam tail portion and another shoulder to rest upon the said lug when the knuckle is closed, and said locking pin having a limited lateral movement and a lug adjacent its lower end for engagement beneath the lower outer surface of the draw head, due to the coöperation of the last mentioned pin shoulder and the inclined surface of the tail lug before strain is thrown on the knuckle and to pressure of the knuckle after strain is applied thereto.
